US00D804721S

(12) **United States Design Patent** (10) Patent No.: **US D804,721 S**
(45) Date of Patent: ** Dec. 5, 2017

(54) **CONTAINER FOR POUCHES OF SMOKELESS TOBACCO**

(71) Applicant: **AZIONARIA COSTRUZIONI MACCHINE AUTOMATICHE A.C.M.A. S.p.A.**, Bologna (IT)

(72) Inventors: **Roberto Ghiotti**, Calderino di Monte San Pietro (IT); **Fulvio Boldrini**, Ferrara (IT)

(73) Assignee: **AZIONARIA COSTRUZIONI MACCHINE AUTOMATICHE A.C.M.A. S.p.A.**, Bologna (IT)

(**) Term: **15 Years**

(21) Appl. No.: **29/559,787**

(22) Filed: **Mar. 31, 2016**

CLAIM

The ornamental design for a container for pouches of smokeless tobacco, as shown and described.

DESCRIPTION

FIG. 1 is an exploded perspective view of a container for pouches of smokeless tobacco and base separated, showing our new design;

FIG. 2 is a top plan view thereof without the lid;

FIG. 3 is a side view thereof without the lid;

FIG. 4 is a side view thereof with the lid; and,

FIG. 5 is a top plan view of the container, shown without the lid and illustrating the pouches of tobacco ready for use. The broken lines in FIG. 5 showing pouches of smokeless tobacco in the container is included for the purpose of illustrating environmental subject matter only and forms no part of the claimed design.
